UNITED STATES PATENT OFFICE.

EDGAR B. GILLELAND, OF KANSAS CITY, MISSOURI, ASSIGNOR OF ONE-FOURTH TO
JOSEPH McSWEENEY, OF COUNCIL BLUFFS, IOWA.

COMMUTATOR BRUSH.

Application filed November 19, 1924. Serial No. 750,931.

This invention relates to an improved commutator brush for motor vehicles, being particularly designed for use on Ford vehicles and seeks, among other objects, to provide a brush which, by reason of superior performance in practical use, will materially increase the efficiency of the engine and eliminate many of the usual ignition troubles.

The invention seeks, as a further object, to provide a brush which may be used in conjunction with the usual shell of a Ford commutator and which, by simply removing the customary contact roller from the timer shaft, may be installed upon the shaft and secured by the same means employed for the roller.

And the invention seeks, as a still further object, to provide a brush which will function with equal efficiency at all engine speeds, which will eliminate uneven or wavy wearing of the contacts of the commutator shell, and wherein the shoe of the brush may be readily removed.

Other and incidental objects will appear hereinafter.

In the drawings:

Figure 1 is a sectional view showing my improved brush in conjunction with the timer shaft and shell of an ordinary Ford commutator.

Figure 2 is a sectional view on the line 2—2 of Figure 1, looking in the direction of the arrows and showing the manner in which the brush is mounted to cooperate with the contacts of the shell.

Figure 3 is a detail perspective view of the device.

Figure 4 is a horizontal sectional view through the shoe.

Referring now more particularly to the drawings, I have shown my brush in connection with the usual timer shaft 10 and commutator shell 11 of a Ford engine. The shaft is provided at its forward end with a reduced stud 12 accommodating a nut 13 which secures a washer 14 employed to overlie a locking pin 15 retaining the pin against displacement. In accordance with present practice, a contact roller is mounted upon the forward end of the shaft and secured by the parts 12, 13 and 14. The usual insulating ring of the shell is indicated at 16 while the several contacts of the shell which are embedded in said ring, are indicated at 17.

The shell is, as is well known, removably

secured over the forward end of the shaft 10 so that the contact roller will cooperate with the contacts 17 of the shell. However, as is also well known, the contact roller soon wears out while the contacts 17 are worn by the roller in such manner that ridges are produced on said contacts. Thus, it is not only necessary to frequently renew the contact roller but also, inefficient and faulty ignition is prevalently experienced. The present invention, therefore, seeks to overcome these troubles.

In carrying the invention into effect, I provide a sleeve 18 which is preferably rolled from a piece of suitable resilient sheet metal so that the sleeve is, therefore, split, and projecting from one end of the sleeve is a supporting arm 19 while from the other end of the sleeve projects an aligned oppositely disposed guide arm 20. At one edge 75 the sleeve 18 is, as seen in Figure 1, formed with a notch 21 and, preferably, the arms 19 and 20 are integral with the sleeve so that, as will be seen, the sleeve with the arms thereon, may be fashioned from a single 80 sheet metal blank. The arms 18 and 19 are bent near their inner ends to extend in opposite directions substantially tangentially with respect to the periphery of the sleeve and the arm 19 is again bent near its outer 85 end to provide a forwardly directed lug 22 while the arm 20 is formed at its outer end with a radially disposed eye 23 standing in angular relation to the latter arm. Mounted upon the arm 19 is a flat flexible steel spring 90 24 which extends freely through the eye 23 of the arm 20 and is detachably secured at one end to the lug 22 by a screw 25. Fixed to the free end of the spring is a substantially semi-cylindrical contact shoe 26 the 95 rounded contact face of which is presented outwardly. Formed in the flat face of the shoe is, as particularly shown in Figure 4, a transverse slot 27 snugly accommodating the adjacent end of the spring. Rising from the bottom wall of said slot is a medial stud 28 which is preferably squared to snugly fit through a correspondingly shaped opening in the spring and is upset for rigidly connecting the shoe with the spring. The free 100 end of the spring is thus countersunk in the flat side of the shoe so that should the stud become slightly worn, the end walls of the slot 27 will nevertheless, coact with the side edges of the spring for limiting the shoe 110

against turning movement. A particularly rigid mounting for the shoe is thus provided. As will be seen, the sleeve 18 is adapted to be slipped over the forward end of the shaft 10 while the notch 21 of the sleeve is adapted to accommodate the pin 15, so that the washer 14 and nut 13 may be applied in the usual manner for securing the brush upon the shell. Thus, the brush may be readily 10 substituted in lieu of the ordinary contact roller.

Attention is now directed to Figure 2 of the drawings. As shown, the spring 24 is supported to curve longitudinally about the 15 axis of the shaft 10 while the shoe 26 is held by the spring to cooperate with the contacts 17 of the commutator shell. Accordingly, when the shaft 10 is revolved the spring will travel endwise around the shaft 20 so that the shoe will be successively drawn over the several contacts of the shell to make efficient electrical connection with each of said contacts. In mounting the spring in the manner shown, localization of stress on 25 the spring is avoided while chattering of the shoe against the contacts 17 of the shell is also obviated. The contacts of the shell will thus be worn smooth with the result that the necessity for renewing the shell at 30 frequent intervals, as now experienced, will be eliminated. When the shoe 26 becomes worn, the screw 25 may be removed and a new spring and shoe installed.

The guide arm 20 is provided for holding 35 the free end portion of the spring against lateral displacement so that the shoe 26 will, at all times, be guided to bear against the insulating ring 16 of the shell to wipe the contacts 17 and, as will be observed, the eye 40 23 is of sufficient height to permit outward swinging of the free end of the spring as the shoe wears. Furthermore, should the engine back-fire, with a consequent reversal

in the direction of movement of the shaft 10, the guide arm 20 with its eye 23 will 45 serve to prevent jamming or crumpling of the spring between the shaft and shell. As will be seen, when the shaft 10 is counter-rotated, the outer end of the eye will be moved into engagement with the spring near 50 its free end, when the arm 20 will serve to brace and retain the free end portion of the spring so that the shoe 26 will be pushed along the surface of the insulating ring 16 in advance of the arm. Accidental fracture 55 of the spring will thus be effectually avoided.

Having thus described the invention, what I claim is:

1. A commutator brush including a split sleeve formed at its ends with oppositely 60 directed arms one provided with an eye, a leaf spring secured at one end to the other of said arms to extend freely through said eye curved longitudinally in substantially concentric relation to the axis of the sleeve, 65 and a contact shoe carried by the free end of the spring.

2. A commutator brush including a sleeve having oppositely directed arms extending therefrom, a spring secured at one end upon 70 one of said arms and having its free end portion guided by the other of said arms, and a contact shoe having a slot seating the free end of the spring and provided with a stud extending through the spring connecting the shoe therewith and locking the shoe against turning movement.

3. A spring arm and shoe assembly for a commutator brush, comprising a shoe having a slot in which the arm is seated, a stud 80 on the side of the shoe opposite the contracting surface, an aperture in the spring through which the stud extends to hold the shoe rigidly in position upon the spring arm.

In testimony whereof I affix my signature.
EDGAR B. GILLELAND. [L. s.]
